(57) **CLAIM**

The ornamental design for a pneumatic carrier, as shown and described.

DESCRIPTION

FIG. 1 is a perspective view of a pneumatic carrier showing our new design;

FIG. 2 is a front elevation thereof;

FIG. 3 is a left side elevation thereof;

FIG. 4 is a right side elevation thereof;

FIG. 5 is a rear elevation thereof;

FIG. 6 is a top plan view thereof;

FIG. 7 is a bottom plan view thereof; and,

FIG. 8 is a perspective view thereof showing the lids in an open position.

The broken lines shown in the drawings define the bounds of the claimed design and form no part thereof.
